LIGHT EMITTING GAS DISCHARGE MATRIX DISPLAY PANEL

Fred E. Mansur, Temperance, Mich., assignor to
Owens-Illinois, Inc., Toledo, Ohio

Filed Sept. 24, 1973, Ser. No. 400,075

Term of patent 14 years

Int. Cl. D14—02

U.S. Cl. D26—5 C

FIG. 2

FIG. 1-3FIG. 2-4

FIG. 1 is a front elevational view of a light emitting gas discharge matrix display panel embodying my new design, the rear being identical to the front shown, as view turned 90;

FIG. 2 is an enlarged fragmentary front elevational view of lower left corner;

FIG. 3 is an elevational view taken from one side thereof, the opposite side being a mirror image of the side shown; and

FIG. 4 is a bottom plan view thereof, the top being a mirror image of the bottom shown.

I claim:

The ornamental design for a light emitting gas discharge matrix display panel, as shown and described.
